SEWALL CABOT, OF BROOKLINE, MASSACHUSETTS

RESISTANCE-TUNED CIRCUIT

Application filed May 28, 1929. Serial No. 366,689.

One object of my invention is to provide a system of electrically tuned circuits comprising fixed inductances, resistances and capacities and in addition a variable resistance which determines the frequency to which the system is maximally responsive. Heretofore, insofar as I am aware, such systems have been tuned by the variation of inductance, capacity or both, which determines the frequency to which the system is maximally responsive.

In my circuit, however, this tuning is accomplished by the variation of a resistance. In order to accomplish this effect one of the resistances must be negative. It is well known to the art that a negative resistance may be obtained from the electrodes of an ordinary vacuum tube with appropriate direct current voltages applied.

In my system, as is usual in tuned systems which contain negative resistance in some form, the circuit may be made stable and any sudden shock set up in it will die away in the form of a damped oscillation, the duration of the damped oscillation being dependent on the value of the negative resistance chosen. With a slightly changed value of negative resistance the circuit becomes a generator of sustained oscillation of the frequency to which it is tuned. Both of these conditions may be of value in radio reception and the last mentioned of value in radio transmission or the generation of sustained oscillations.

In order to more fully disclose my invention, I show in the figure of the drawing which accompanies and forms a part of this specification, a circuit which may be utilized to tune a radio antenna to be maximally responsive to any desired frequency within a band of desired frequencies or may be used to cause the antenna to send out an electromagnetic wave of any desired frequency within a band, said frequency being dependent on the particular adjustment of an adjustable resistance.

In the figure, the source of negative resistance comprises a vacuum tube 1, 2, 3 together with sources of electromotive force A and B, having contacts 4 and 10 to determine the

direct current polarizing voltages on the electrodes 2, 3 and a filament rheostat R_7 to govern the electron emission from the filament. This structure forms the equivalent of a negative resistance R_6 shunted by a capacity C_1 . 55 This negative resistance may be given any value within limits by appropriate adjustment of the filament resistance R_7 and the contacts 4 and 10. If the interelectrode capacity C_1 is insufficient for the band of frequencies to be covered it may be augmented by connecting additional capacity between electrodes 2 and 3.

In series with electrode 3 to ground 9 are connected a fixed inductance L_1 shunted by a fixed resistance R_1 , an adjustable resistance R_2 and the circuit between points 6 and 9 which may be made a fixed and constant resistance for all frequencies provided that

$$R'_2 = R'_3 = \sqrt{\frac{L_2}{C_2}}.$$

In the circuit between points 6 and 9, C_2 is the antenna capacity (which may be augmented if desired to cover a particular desired band of frequency response) and C is a by-pass condenser of negligible reactance to the band of frequency response. L_2 is a fixed inductance.

In order to make the circuit maximally responsive to alternating currents of a definite predetermined frequency, the constants thereof are so chosen that for said frequency the effective negative resistance of the circuit 6, 5, 3, 9' is approximately equal to the effective positive resistance between the points 6, 9, which as aforesaid, is equal to

$$\sqrt{\frac{L_2}{C_2}},$$

the term "effective" being employed in its usual well-known mathematical sense and signifying (in the present instance) the resistance component of an impedance. The values of said constants may be determined by developing the equation for the impedance Z around the closed circuit 9—6—5—3—2—9', the points 9 and 9' both being grounded. The electromagnetic constants of the par-

allel-branch circuit, the terminals of which are 6 and 9, are so chosen that the resistance between the points 6 and 9, plus the resistance R_2 is equal to

5

$$K_2 \sqrt{\frac{L_1}{C_1}}$$

where K_2 is a constant hereinafter more fully defined.

- 10 The resistance between the points 3 and 2, or what is the same thing, between the points 3 and 9', which, as aforesaid, is the negative resistance provided by the vacuum tube is, by appropriate adjustment of the filament 15 resistance R_7 and the contacts 4 and 10, made equal to

$$-(1+\Delta) \sqrt{\frac{L_1}{C_1}},$$

- 20 where Δ is a number very small compared to unity.

The resistance between the points 5 and 3 is so chosen and designed as to be equal to

25

$$\sqrt{\frac{L_1}{C_1}}.$$

- 30 The total impedance of the circuit, designed by giving the electromagnetic constants thereof the values above set forth, may be determined for any frequency f as follows:

If the impedance of that portion of the

35

$$Z = \frac{\sqrt{\frac{L_1}{C_1}}(-j\frac{K_4}{m})}{K_4 - j\frac{1}{m}} + \frac{\sqrt{\frac{L_1}{C_1}}(jK_3m)}{K_3 + jm} + \sqrt{\frac{L_1}{C_1}}(K_2) \quad (1)$$

40

$$= \frac{\sqrt{\frac{L_1}{C_1}}(K_4 - jK_4^2m)}{1 + K_4^2m^2} + \frac{\sqrt{\frac{L_1}{C_1}}(K_3m^2 + jK_3^2m)}{K_3^2 + m^2} + \sqrt{\frac{L_1}{C_1}}(K_2) \quad (2)$$

- 45 circuit between the points 3 and 9' (i. e., between the points 3 and 2) is represented by Z_a , the impedance between the points 3 and 5 by Z_b , and the impedance between the points 5 and 9 by Z_c , the total impedance of the circuit will be

50

$$Z = \frac{\sqrt{\frac{L_1}{C_1}}[K_2(m^2 + 1) + m^2 - 1 - j2\Delta m]}{m^2 + 1} \text{ (approximately)} \quad (3)$$

55

$$Z = Z_a + Z_b + Z_c$$

$$Z_a = \frac{R_6(-j\frac{1}{C_1\omega})}{R_6 - j\frac{1}{C_1\omega}}$$

60

$$Z_b = \frac{R_1(jL\omega)}{R_1 + jL\omega}$$

$$Z_c = R_2 + \sqrt{\frac{L_2}{C_2}}$$

65 where $\omega = 2\pi f$.

To simplify the equations the factor

$$\sqrt{\frac{L_1}{C_1}}$$

is introduced into all expressions for the actual resistances of the portions of the circuits between the pairs of numbered points 3-9', 3-5, and 5-9, indicated on the diagram, and this factor is multiplied by the constants K_4 , K_3 or K_2 as the case may be, to get the actual resistances in ohms between each pair of said points.

The equations may be further simplified by writing

$$\omega\sqrt{L_1C_1} \text{ as } m,$$

R_6 , the resistance between the points 3 and 9', as

$$K_4 \sqrt{\frac{L_1}{C_1}},$$

R_1 , the resistance between the points 3 and 5, as

$$K_3 \sqrt{\frac{L_1}{C_1}},$$

and

$$R_2 + \sqrt{\frac{L_2}{C_2}} \text{ as } K_2 \sqrt{\frac{L_1}{C_1}}.$$

The total impedance of the circuit may then be expressed as

If K_3 is unity and K_4 is $-(1+\Delta)$ where Δ is a number very small compared to unity as aforesaid

$$1 + K_4^2m^2 = K_3^2 + m^2 \text{ (approximately)}$$

and the total impedance becomes

$$Z = \frac{\sqrt{\frac{L_1}{C_1}}[K_2(m^2 + 1) + m^2 - 1 - j2\Delta m]}{m^2 + 1} \text{ (approximately)} \quad (3)$$

In order to determine the resonant frequency with a known value of K_2 , or to determine the value of K_2 for a known frequency, the resistive component of the impedance is equated to zero, viz,

$$\frac{\sqrt{\frac{L_1}{C_1}}[K_2(m^2 + 1) + m^2 - 1]}{m^2 + 1} = 0 \quad (4)$$

whence

$$K_2 = \frac{1-m^2}{1+m^2}$$

5 and

$$m = \sqrt{\frac{1-K_2}{1+K_2}}.$$

From this it will be seen that if we adjust 10 the resistance R_2 so that

$$K_2 = \frac{1-m^2}{1+m^2}$$

the resistive component disappears and the 15 reactive component becomes

$$-j\sqrt{\frac{L_1 C_2 \Delta m}{m^2 + 1}}$$

20 which is a relatively small quantity dependent on the value Δ and ensures a relatively large current value with small impressed electromotive force in the circuit.

25 The maximum frequency f to which the circuit may be tuned is as follows:

Let

$$\theta = \text{the ratio } \sqrt{\frac{L_2 C_1}{C_2 L_1}}$$

30 then

$$\omega_{\max.} = \sqrt{\frac{1-\theta}{1+\theta}} \left(\frac{1}{\sqrt{L_1 C_1}} \right) = 2\pi f_{\max.}$$

The minimum frequency will be zero.

35 In order to determine the transient effects and stability of the circuit, it will be necessary to develop the differential equation of the circuit along the usual lines (see Morecroft, Principles of Radio Communication, 40 1927, chapter 111).

The current I due to releasing a charge of E volts in the capacity C_1 in the circuit will be

$$45 I = \left(\frac{E}{\omega_0 L_1 (1+K_2)} \right) e^{-\alpha t} (\sin \omega_0 t + \omega_0 \sqrt{L_1 C_1} \cos \omega_0 t),$$

where

$$\alpha = \frac{\Delta}{2\sqrt{L_1 C_1}} \text{ approximately}$$

50 and

$$\omega_0 = \sqrt{\frac{1-K_2}{(1+K_2)LC}} \text{ approximately.}$$

55 It will be noted from this that the effects of a "shock" die out with time if Δ is a positive number and that the circuit becomes a generator of local oscillations if Δ is a negative number.

60 Having thus described an illustrative embodiment of my invention, without however limiting myself thereto, what I claim is:

65 1. A tunable circuit comprising in combination two circuits connected in parallel, one of said circuits including a capacity and a positive resistance connected in series and

the other including an inductance and a positive resistance connected in series, means whereby an electromotive force may be impressed in one of said circuits, said positive resistances each being approximately equal, 70 in ohms to the square root of the ratio of said inductance to said capacity, an effective negative resistance connected in parallel with said circuits, and means for adjusting the value of the effective negative resistance so 75 that at a definite predetermined frequency said negative resistance is approximately equal in value to said positive resistances.

2. An electrical network comprising a parallel-branch circuit, one branch of which includes a serially-connected inductance and resistance and the other a serially-connected capacity and resistance, each of said resistances being approximately equal in ohms to the square root of the ratio of said inductance 80 to said capacity, and a negative resistance connected across the terminals of said parallel-branch circuit of value approximately equal to that of either of said positive resistances. 85

3. The method of rendering an electric circuit maximally responsive or self-oscillatory at a predetermined definite frequency which consists in adjusting a positive resistance in said circuit so that the value K_2 in the expression 90

$$K_2 \sqrt{\frac{L_1}{C_1}}$$

representing the resistance of a portion of 100 said circuit, is equal to

$$\frac{1-m^2}{1+m^2}$$

where $m = \omega \sqrt{L_1 C_1}$, $\omega = 2\pi$ times the frequency of an alternating voltage impressed upon said circuit, C_1 is the capacity between the grid and plate of a thermionic tube included in said circuit, and L_1 is the value of an inductance connecting the plate of said tube to 110 said circuit. 105

4. An electrical network comprising a parallel-branch circuit, one branch of which includes a serially-connected inductance and resistance and the other a serially-connected capacity and resistance, each of said resistances being approximately equal in ohms to the square root of the ratio of said inductance to said capacity, means for impressing an alternating electromotive force on one branch of said parallel-branch circuit, a circuit serially connected with said parallel-branch circuit, and means included in the last-mentioned circuit for neutralizing the effective positive resistance of said parallel-branch circuit at a definite predetermined frequency. 115 120

5. An electric circuit maximally responsive or self-oscillatory at a definite predetermined frequency comprising a serially-connected inductance, capacity and variable re- 130

- sistance, a negative resistance connected in shunt to said capacity, the value in ohms of said negative resistance being approximately equal to the square root of the ratio of said inductance to said capacity, and a positive resistance connected in shunt to said inductance, said positive resistance having approximately the same value as said negative resistance.
- 10 6. An electric circuit maximally responsive or self-oscillatory at a definite predetermined frequency comprising a serially-connected inductance, capacity and variable resistance, and resistances of opposite sign connected, respectively, in shunt to said inductance and capacity, each of said resistances being approximately equal to the square root of the ratio of said inductance to said capacity.
- 15 7. A resistance-tuned circuit comprising an effective negative resistance and a positive resistance connected in series, and means for rendering said effective negative resistance substantially equal in value to the positive resistance of said circuit for a definite predetermined frequency only.
- 20 8. A resistance-tuned circuit comprising a fixed inductance, a resistance, and a negative resistance serially connected, a capacity in shunt to said negative resistance, a resistance in shunt to said fixed inductance, and an adjustable positive resistance in series with said negative resistance for rendering the effective value of said negative resistance substantially equal to that of the total positive resistance of the circuit for a definite predetermined frequency only.
- 25 9. An electrical network comprising a parallel-branch circuit, one branch of which includes a serially connected inductance and resistance, and the other a serially connected capacity and resistance, each of said resistances being approximately equal in ohms to the square root of the ratio of said inductance to said capacity, a negative resistance and an inductance connected in series with each other and across the terminals of said parallel-branch circuit, a capacity shunting said negative resistance, a resistance shunting said inductance, the value in ohms of said last-mentioned resistance being equal to the square root of the ratio of the last-mentioned inductance to said capacity, and the value in ohms of said negative resistance being slightly greater than the square root of the ratio of the last-mentioned inductance to said capacity, and an adjustable resistance connected in series with said negative resistance and inductance for rendering the effective value of said negative resistance substantially equal to that of the total positive resistance of the circuit for a definite predetermined frequency only.
- 30 10. A tuned or self-oscillatory circuit comprising in combination, a parallel-branch circuit comprising a serially-connected resistance and capacity in one branch and a serially-connected resistance and inductance in the other branch, each of said resistances being equal to the square root of said inductance divided by said capacity, an impedance connected across the terminals of said parallel-branch circuit, said impedance comprising a positive resistance, a negative resistance, an inductance and a capacity, the reactance component of said impedance being very small or negligible for all frequencies within a given band and the resistance components thereof being negative, and adjustable means whereby said resistance component of said impedance is made substantially equal to the positive resistance of said parallel-branch circuit for one only of the frequencies within said band.
- 35 11. A radio system comprising in combination a parallel-branch circuit, one branch of which includes a serially-connected inductance and resistance and the other a serially-connected capacity and resistance, each of said resistances being approximately equal in ohms to the square root of the ratio of said inductance to said capacity, an antenna electrically associated with said parallel-branch circuit, and a circuit including a source of negative resistance having its terminals connected, respectively, to the junctures of said parallel-branch circuit.
- 40 In testimony whereof, I have hereunto subscribed my name this 27th day of May, 1929.
